C. BEVELOT.
THRASHING MACHINE.

No. 269,622.

Patented Dec. 26, 1882.

UNITED STATES PATENT OFFICE.

CLEMENT BEVELOT, OF EAST ST. LOUIS, ILLINOIS.

THRASHING-MACHINE.

SPECIFICATION forming part of Letters Patent No. 269,622, dated December 26, 1882.

Application filed July 24, 1882. (Model.)

To all whom it may concern:

Be it known that I, CLEMENT BEVELOT, of East St. Louis, in the county of St. Clair, and in the State of Illinois, have invented certain new and useful Improvements in Thrashing-Machines; and I do hereby declare that the following is a full, clear, and exact description thereof, reference being had to the accompanying drawings, and to the letters of reference 10 marked thereon, making a part of this specification.

This invention relates to certain improvements in thrashing-machines; and it has for its object to dry the grain when damp, and 15 thus prevent it from clogging the machine; to remove the straw from the thrashing mechanism quickly and effectually; to beat out any of the grain carried off by the straw and save the same, and to provide for adjusting the elevator-belt, as more fully hereinafter specified. These objects I accomplish by the means illustrated in the accompanying drawings, in 20 which—

Figure 1 represents a side elevation of my 25 machine; Fig. 2, a longitudinal vertical sectional view thereof, and Fig. 3 a detached view, showing the drying devices for heating and drying the grain.

The letter A indicates the frame of the apparatus or machine, which is of the ordinary 30 or any approved construction; and B, a feed-hopper located at the forward end of the machine.

Just back of the feed-hopper are located the 35 thrashing devices, which consist of a rotating slatted drum, C, having a series of pins or projections, D, on its periphery, and a curved plate, E, located below the drum, and provided with a series of pins or projections, F. The 40 drum is mounted upon a shaft, G, journaled in bearings H, and provided with a driving-pulley, by which it may be put in motion. The plate E is pivoted at L, and at its front edge is connected with a lever, M, located at the 45 front of the apparatus, by means of which the plate may be adjusted as required. Just behind the thrashing devices are located two rollers or carriers, N, which have longitudinal angular ribs P, and which are geared to turn 50 in opposite directions, so as to seize and carry

forward the straw after thrashing. The peculiar form of the ribs or longitudinal peripheral edges of said carrying-rollers serves to more readily grasp the straw and give it a reliable and positive forward advance or movement, insuring its safe delivery upon the first elevator-belt. 55

The letter R indicates an elevator-belt running over rollers S, suitably journaled in the machine. The journals of the lower rollers 60 have their bearings in movable boxes T, which may be adjusted by means of set-screws U to regulate the tension of the belt.

The letter W indicates a beater located at the upper end of the aforementioned belt, 65 having its journals mounted in suitable bearings, and provided with gearing, by means of which it may be rotated, so as to beat up the straw as it passes along.

Y indicates another elevator-belt, which is 70 designed to carry off the straw finally. At the upper end of the last-mentioned belt is located a beater, A', which, as it rotates, beats down upon the straw and beats out any loose grain carried over, delivering it through the passage 75 B' to the inclined blast-deflecting and delivery board B², from whence it discharges into the winnowing-sieve C, which receives the thrashed grain from the first-mentioned elevator-belt. 80

D' indicates a drier, consisting of a double-walled semi-cylindrical chamber, located transversely to the machine, and secured thereto, between the side beams of the frame, by any suitable means. Between the walls of the said 85 chamber is located a serpentine heating-pipe, E', which communicates by means of the tube E² (seen in Fig. 1) with a steam-generator—as, for instance, the boiler used to supply steam to the engine employed in operating the 90 thrasher.

Within the concavity of the drying-chamber is placed a worm-screw or conveyer, the shaft thereof being suitably journaled in bearings secured to the frame of the machine. A 95 discharge-passage, by which the grain is allowed to escape from the chamber, is located at one side thereof, as indicated by the letter f in Fig. 1.

It will be observed by reference to Fig. 2 100

of the drawings, first, that by reason of the location in the machine of my drying-chamber the grain may be delivered directly from the shoe into the said chamber; and, secondly, 5 that by reason of the peculiar construction of the chamber I am able to obtain a large drying-surface, which occupies but a small space in the machine, thus rendering my drying-chamber peculiarly applicable to a thrasher, 10 as its construction admits of its being located in the most desirable part of the machine, and in a space which is usually of small dimensions. Owing to this peculiarity of construction, I am able to supply the thrashers already in use with a drying-chamber which 15 possesses a large heating-surface, and which occupies but a small space.

G' indicates an elevator for conveying the grain back to be repassed through the machine.

20 The letter H' indicates a fan, suitably mounted and geared, to supply the air for winnowing.

Having thus described my invention, what I claim, and desire to secure by Letters Patent, 25 is—

1. In a thrashing-machine, the combination of the thrashing-cylinder and the concave with

the carrying-rollers, longitudinally ribbed, as described, and located in close proximity to the thrashing mechanism, the said rollers being geared to rotate in opposite directions, and 30 adapted to grasp and carry the straw, in the manner substantially as herein shown and set forth.

2. In a thrashing-machine, the combination of the thrashing-cylinder and the concave 35 with the carrying-rollers, constructed and located substantially as shown, and the elevating-belt, the said rollers being adapted to receive the straw from the thrashing mechanism and deliver it upon the belt, as described, 40 and for the purpose set forth.

3. In a thrashing-machine, the combination, with the fan and grain-shoe, of the semicircular beater and propelling-screw, substantially as and for the purposes specified. 45

In testimony whereof I affix my signature, in presence of two witnesses, this 24th day of July, 1882.

CLEMENT BEVELOT.

Witnesses:

J. J. McCARTHY,
JOSEPH J. HEINE.
